UNITED STATES PATENT OFFICE.

SARGENT P. MARSH AND ELMER E. MARSH, OF CINCINNATI, OHIO.

DETECTION-SIGNAL.

1,329,053.

Specification of Letters Patent. Patented Jan. 27, 1920.

Application filed February 15, 1918. Serial No. 217,357.

To all whom it may concern:

Be it known that we, SARGENT P. MARSH and ELMER E. MARSH, citizens of the United States, and residents of Cincinnati, in the 5 county of Hamilton and State of Ohio, have invented certain new and useful Improvements in Detection-Signals, of which the following is a specification.

Our invention relates to alarms, indica- 10 tors or signals, and its object is to indicate surreptitious movement, and especially of automobiles. A further object of our invention is to indicate such movement whether the automobile be moved by the 15 use of its own motive apparatus or be towed or otherwise moved on its driving wheels. It is also our object to provide this alarm, so that it can be readily set by the rightful user of the vehicle so as to be in operative 20 condition or out of operative condition, acc- cordingly as the vehicle is to be left alone or to be used by the rightful user. A still further object is to afford the alarm in a manner that will be certain to attract attention even in very noisy places as on the 25 streets of large cities; and to effectively guard against derangement of the alarm apparatus or its operative mechanism. It is also our object in some examples to pro- 30 vide a device of this character which can be readily applied to a completed automobile by removing one of the parts thereof and substituting our device therefor. Other ob- 35 jects will appear in the course of the de- scription.

Our invention consists in the combination of parts and in the details of construction and arrangement of parts as will herein- 40 after be more fully described and claimed.

In the drawings:

Figure 1 is a sectional plan view of part of an automobile with our invention applied thereto, the section being on a horizontal plane corresponding to the line 1—1 of 45 Fig. 2;

Fig. 2 is a rear elevation of the apparatus as shown in Fig. 1;

Fig. 3 is a partial plan view similar to Fig. 1, but showing the extreme top of 50 the casing, which is omitted in Fig. 1;

Fig. 4 is a rear elevation similar to Fig. 2, but showing a modification;

Fig. 5 is an upright transverse section on a plane corresponding to the line 5—5 of 55 Fig. 2, and also approximately showing the

modification of Fig. 4 on a plane correspond- ing to the line 5—5 of that figure;

Fig. 6 is a plan view similar to Fig. 1, but showing another modification of our inven- 60 tion as applied to a modified automobile part;

Fig. 7 is a partial vertical longitudinal section on a plane corresponding to the line 7—7 of Fig. 6; and

Fig. 8 is a lesser partial section like Fig. 65 7 showing another modification.

In carrying out our invention with the objects hereinbefore mentioned, the use of a sound-producing device is involved, and, as such device, we prefer to employ a whistle 70 of the kind used for signaling by police- men; since the sound made thereby is readily recognized by many people and by every police officer.

Because automobile thieves are not 75 thwarted by rendering the motive apparatus of the automobile inoperative, but will hitch to it a horse or other automobile and tow it away, we provide operating means for the sound-producing device, be it such a whistle 80 as just described, or other kind of device which will be actuated by some part inti- mately connected with the driving wheels of the vehicle. As here shown, the operative connection is made with the differential 85 mechanism and the entire device is located within and protected by the casing of said mechanism.

As shown in Figs. 1 to 5, the rear or driving axles 1 of the automobile are dif- 90 ferentially connected by suitable gears con- tained in the inner revolving casing 2, and which being well known, need not be shown or further described; it only being neces- sary for the purposes of our des ription to 95 mention that whenever either one of the driving wheels and its driving axle 1 is turned, rotation is imparted to this casing 2; and that at no time in the normal use of the automobile is either one of these 100 axles 1 ever disconnected from this casing 2. Fixed to and concentric with the casing 2 is the large bevel ring-gear 3 meshing with the driving pinion 4 on the rear end of the driving or tail shaft 5 of the automo- 105 bile, which, as is well understood, runs for- ward to the transmission me hanism through which it is variously operatively connected with the motor of the vehicle. Generally when the automobile is stopped, this shaft 5 110

is disconnected from the motor by proper setting of the transmission mechanism; so that this shaft 5 is free to turn along with the axles 1 through the intermediary of the differential gears. Thus, hauling the automobile on its own wheels by extraneous motive power is very convenient and offers good opportunity to thieves to make away with the vehicle under the guise of repair men, 10 even in crowded places in large cities.

As shown in Figs. 1 to 3, and as Fig. 5 also serves to illustrate the interior construction of, the differential casing, that encloses the inner shell or casing 2 and its associated gears 3 and 4 and forms bearings for the axles 1 and shaft 5, is in right and left parts 6 and 7 joined together in a vertical plane through the center line of the shaft 5 from front to rear, and having their opposite ends fixed to the hollow axles 8 around the axles 1 with the bearings 9 for these axles 1 and the bearings 10 for the differential shell or casing 2 and large gear 3 inside of these opposite ends. At the front 25 these parts 6 and 7 support the bearing 11 for the driving or tail shaft 5.

As these casings are usually constructed, and as is well known, any diametral cross section will appear substantially as seen in Fig. 1, excepting the bearing 11 of the shaft 5 at the front. As shown in this example, however, the upper half of each part 6 and 7 of the differential casing is provided with an enlargement 12 or 13, respectively, extending in the form of a high substantially straight-topped ridge from front to rear across the respective part; so that when the parts are brought together a rather high and long box-like casing is formed, closed 35 on all sides outwardly, but merging with the original walls of the parts 6 and 7 and opening into the interior of the differential casing formed by bringing these parts together.

The right hand part 6 next to the ring-gear 3 has a downwardly projecting flange 14 extending along the junction of the enlargement 12 with the main wall of the part 6 from front to rear and recessed in its middle part to clear the gear 3. Fixed to 40 this flange 14 is a frame 15 with rings 16 at its front and rear ends, and rings 17 nearer its middle and equally spaced forwardly and rearwardly from the vertical center line of the casing. Supported in these 45 rings in horizontal alinement along the casing enlargement from front to rear are the cylinders 18. The middle rings 17 also have extending down from them and joining them together, a bracket 19 which has 50 on the vertical center line of the casing an upper bearing 20 and a lower bearing 21 with a large slot 22 between them, which is occupied by a bevel-gear 23 having the upper and lower ends of its hub journaled in 55 the bearings 20 and 21, respectively. This

bevel-gear 23 meshes with the large ring-gear 3 of the differential mechanism.

A crank 24 has a short shaft 25 journaled partly in the upper bearing 20, and partly in the upper end of the hub of the gear 23 and 70 held down by a flange 26 extending under a shoulder in the upper part of said bearing 20; this crank having a wrist 27 extending upward. Plungers or pistons 28 fit closely inside the cylinders 18 and a cross-head 29 75 has opposite ends connected to the pistons by short struts 30, while in its middle it has the transversely slotted yoke 31 with the wrist 27 bearing in the slot thereof. A suitable screw 32 and washer 33 hold the yoke 80 and crank operatively together.

The outer ends of the cylinders 18 have heads 34 each of which is provided with an inward check-valve 35 or 35' and an outward check-valve 36. Pipes 37 and 38 lead from 85 the respective outward check-valves 36 and come together in a single pipe 39 leading into the whistle 40 which is mounted on the top 41 that joins the rings 17 of the frame 15 together above the cylinders 18 at the 90 middle of the casing. Whistles which would be suitable for our purpose being of varied construction, and the one which we prefer being very well known, it is unnecessary to show the details of construction of the 95 whistle; it being sufficient to understand that air in passing from the mouth-piece 42 out through the slots 43 near the middle of the body of the whistle produces the desired sound. 100

The lower end of the shaft 25 of the crank 24 is provided with downwardly extending clutch-teeth 44 inside the hub of the gear 23. The lower end 45 of the opening through the hub of the gear 23 is squared, and a slidable 105 shaft 46 has a squared middle part fitting in the square part 45 of the hub, and has its upper end provided with clutch-teeth 47, which will mesh with the teeth 44 and cause the crank shaft 25 to turn with the slidable 110 shaft 46 if the slidable shaft is slid up in the hub. A setting lever 48 is fulcrumed on a pin 49 in a lug 50 extending down from the front end of the bracket 19 with a short forward arm 51 compressing a strong 115 helical spring 52 up against a ledge 52' on the upper part of the rear end of said bracket 19; and with a long rear arm 53 which has, in suitable position, an opening down through it through which the slid- 120 able shaft 46 has a neck 54 extending with a head 55 thereon under the lower side of the lever-arm 53.

Mounted on the interior of the rear wall of the casing enlargement by means of a 125 forwardly extending bracket 56 on the wall, is a suitable lock 57 with a cylinder 58 extending rearwardly through a suitable opening in the casing wall; so that the exposed outer rear end of the cylinder 58 may receive 130

the key 59. The bolt 60 of this lock is shot downward from the bottom of the lock inside the casing, and the rear end part of the rear lever-arm 53 bears against the lower 5 end of this bolt 60. Suitable locks for our purpose being of various construction, and the one which we prefer to use being of well known construction, it is unnecessary to show or describe the interior details thereof, 10 it being sufficient to understand that the bolt 60 may be shot down or up only by the use of the proper key 59 inserted into the cylinder 58.

The top of the casing enlargement preferably is provided with a suitable opening or openings to allow free passage of the sound waves from the whistle 40. Preferably, these passages are numerous and very small in diameter; as here shown, being the 20 small holes 61 vertically through the casing top and having their outer ends covered by a fine mesh wire screen 62 to prevent the entrance of foreign matter to the casing and to prevent such matter clogging these openings. 25

As long as the bolt 60 is shot downward, the long rear arm 53 of the setting-lever 48 holds the slidable shaft 46 down, so that its teeth 47 do not mesh with the teeth 44 of 30 the crank shaft 25. But if the bolt 60 is shot upward by a proper application of the key 59, the spring 52 acting on the front arm 51 of the setting lever throws the rear arm 53 upward and with it the slidable 35 shaft 46, meshing its teeth 47 with the teeth 44 of the crank shaft 25. With the parts in these positions, as soon as the wheels of the automobile turn, with the large ring-gear 3 turning with them, the bevel-gear 23 of 40 our device will be turned rapidly, and with it, through the clutching of the shafts 46 and 25, will turn the crank 24, which, by its engagement in the slotted yoke 31 connected to the pistons or plungers 28, will 45 reciprocate these pistons or plungers very rapidly in the cylinders 18. These cylinders with their reciprocating pistons thus constitute a double acting pump, and the alternate discharges of air through the 50 pipes 37 and 38 will amount to a continuous blast of air through the pipe 39 into the whistle 40, sounding the whistle very loudly and continuously as long as the 55 wheels of the vehicle continue to turn, with the parts in the described position.

It is therefore unnecessary for the rightful user of the vehicle having the key 59 to do any more than shoot the bolt 60 downward when he is to leave the vehicle unattended; and any movement of the vehicle causing its rear wheels to turn will be indicated by a sound from the whistle 40. With the gear 23 of our device rather small relative to the ring-gear 23, the operation of the double acting pump will be

very rapid even with the very slow turning of the vehicle wheels; so that even a slight or slow movement of the vehicle will cause the alarm.

Such a loud and continuous blast of a 70 whistle is certain to attract attention, not only of police officers, but of the public in general; so that it would be practically impossible for a thief or a surreptitious user of a vehicle provided with our invention, 75 properly set as above described, to travel very far with it without being apprehended. In fact, in most municipalities, the blowing of a whistle on the public thoroughfares is prohibited by law, except by 80 police officers, so that such a sounding of the whistle in such communities would only mean to a police officer that his attention is to be given to the vehicle producing the sound. A rightful user forgetting to release the device from its sounding condition 85 will be at once reminded of the condition; and if he does not release the device, he himself will be quickly stopped by a police officer and compelled to prove his rightful 90 use of the vehicle by producing the key and properly setting the device for rightful use. It will thus be seen that practically the only means of escaping with such a vehicle is to actually have the key to unlock or unset its 95 alarm device. The security, of course, depends upon the reliability of the lock against picking or disruption; but, as is well known, locks of the kind herein indicated are very dependable as regards both 100 of these methods. Or, a permutation lock may be used.

Furthermore, if the lock 57 be knocked entirely loose from its fastening, which in itself can be made very difficult by secure 105 bolting of the lock to the casing side, the result is to leave the device in its set position. Even if it were not set when the lock is knocked loose, the removal of the lock with its downwardly extending bolt 60 110 would permit the device to become set for sounding the alarm. It will thus be seen that having the downward position of the bolt to set the device for rightful use is better than a reverse relation, in which a displacement of the lock by punching through 115 the casing opening might release the alarm-sounding device.

Derangement of the whistle 40 is made difficult by the smallness of the openings 61. 120 It will be understood that openings in the casing wall for the passage of the sound waves are not essential; since these will be very readily transmitted by the vibration of the casing walls. However, clogging of 125 these openings by collection of foreign matter on the screen 62 will be quickly eliminated by the discharge of air from the whistle at any time it becomes necessary for the whistle to operate. Intentional clogging of 130

the openings by the wrongful user of the vehicle will somewhat reduce the intensity of the sound, but not sufficiently to avoid detection; and will be a reasonably sure indication of the guilt of the person as soon as he is detected. Any tampering with the mechanism by making openings in the casing, of course, requires a time and labor consuming operation impracticable to one 10 stealing or wrongfully using an automobile. Such tampering is readily distinguished, by any onlooker, from repair operations, and would be almost sure to result in immediate detection of the person before 15 he completed the operation.

In the modification shown in Fig. 4, the left part 7' of the differential casing is as it is found on the automobile; and only the right hand part 6' is modified; it being provided 20 with the entire enlargement 12' to contain the sound-producing device and its mechanism, which, with the exception of being inclined over toward the large ring-gear 3 and consequently provided with a much 25 smaller gear 23', are approximately as just described, as is shown in full detail in Fig. 5, which serves to illustrate either the example of Figs. 1 to 3, or that of Fig. 4. The advantage of this construction and arrangement 30 will be appreciated when it is recognized that our invention may thus be applied to a vehicle already completed and in use, merely by removing the right hand part of the differential casing from the hollow 35 axle 8 at that side and substituting our part 6' of the casing properly attached to the hollow axle 8 and containing the mechanism in position for properly meshing its gear 23' with the large ring-gear 3 of the differential 40 mechanism.

In Figs. 6, 7 and 8 we illustrate another modification of the mounting and inclosure of our invention by which it is adapted to be readily applied to a differential mechanism 45 having a casing of another type which does not separate on a vertical plane from front to rear, but is made up of a middle part unitary with the hollow axles, and front and rear parts separable from this middle 50 part.

Thus, the hollow axles 63 surround the vehicle axles 1 and are integrally joined at the middle by a large ring-shaped part 64 with large openings at its front and rear. 55 Across its front is bolted the casing part 65, and the driving shaft 5 is journaled in the bearing 66 in said part 65; while the rear is ordinarily closed by a plain plate approximately conforming to the segment of a 60 sphere; the completed casing being generally substantially spherical in its general formation, accommodating, inside, the revolute differential shell 2 carrying the large ring-gear 3 in mesh with the driving-gear 65 4 on the driving-shaft 5; and the axle 1 and

the differential parts having their suitable bearings 67 inside the opposite casing ends.

For the application of our invention to a differential construction of this type, we substitute for the plain rear plate a rear plate 70 68 of substantially the same form peripherally and laterally; but having up and down medianly the ridge-like box-shaped elongated enlargement 69 substantially the same as the corresponding enlargement 75 formed by the parts 12 and 13, or the unitary enlargement 12', in the preceding examples. This casing enlargement contains the sound-producing device and its operating mechanism substantially of the same detailed construction as in the preceding examples with a few exceptions which will be described.

The mechanism is, of course, vertical instead of longitudinal, incident to its inclusion in the rear end of the casing rather than in the top, as in the preceding examples; and, so as not to seal the lower pump inlet 35', a pipe 70 leads from it up well above the level of any substance that would be contained in the differential casing for lubricating the differential gears as well as the operative parts of our device. Moreover, if necessary to obviate splashing of oil out through the passages 61, they may be located 80 up near the top of the casing in the rear side thereof, as the passages 61' in Fig. 8; in which case it is preferable to move the whistle 40 up close to the top of the casing, connecting it to the pump cylinders by a 85 shortened upper pipe 38' and a lengthened lower pipe 38'; and the frame 15' being modified accordingly to support the whistle 90 40 in its elevated position. This elevation of the whistle also obviates any serious interference therewith by the lubricant contained in the differential casing. Also, with the whistle slots 43 above the lowermost passage 61 or 61', a rise of the oil in the casing 95 above the level of these slots 43 is hindered 100 since the oil would run out through the passage 61 or 61' before reaching this level.

In this type of casing, this rear plate is, of course, readily removable by merely unbolting it; being provided in this way for 115 convenient access to the differential gears which is not afforded by the type of casing treated in the preceding examples. Such convenient removal would, of course, be unfavorable to the security of our device mounted in 120 such a casing. We provide therefore, for locking this removable rear section of the differential casing in place at the same time the device is set for producing the alarm.

As here shown, this locking is provided 125 for by using a lock 71 which has its bolt 72 adapted to be shot out of its casing at one side or the other. This lock 71 is mounted at the top of the rear casing section in such an inclined position, on a suitable pedestal 130

73 integral with the casing section, that its bolt 72, if shot upward, engages behind the edge of the rear wall of the middle part 64 of the casing, in which edge is preferably a notch 64' receiving a lug 73' of the pedestal 73. The lower side of the rear casing section 68 has, on its interior, a forwardly and downwardly projecting hooked lug 74 that engages with the edge of the wall of the middle part 64 at the bottom, preferably in a notch 64'' therein.

The notches 64' and 64'' are readily filed in the part 64, and prevent the rear section from being slid sidewise to derange the 15 gearing, were the section unbolted, although not unlocked. Also, were the gear 23 not exactly concentric with the bolt-flanges, it might be entirely unmeshed, under such a condition, by turning the section around. 20 The lugs in the notches prevent this. Moreover, as will be seen, any excessive turning of that kind will merely release the setting lever and render the alarm operative.

When the lock-bolt 72 is retracted downwardly, the rear section 68 may be readily bolted in place upon or removed from the middle part 64; the gears 23 and 3 meshing and unmeshing readily.

The pedestal 73 has, continuous with it outside the top of the casing section 68, a hump 75, and forwardly and downwardly through this hump 75 and pedestal 73 is the passage out through which extends the cylinder 76 of the lock 71 for access of the key 77. The lock is very securely bolted in place on the pedestal 73 and the passage thereto being very long, forcible removal of the lock by punching it inward of the casing is very difficult.

40 Furthermore, this lock is made to also operate the setting-lever 48', which, in its connection with the slidable shaft 46 and therebelow, is the same as the setting-lever 48 of the preceding examples and to the rear of 45 its connection. The longer arm 53' of this setting-lever 48', however, is modified from the arm 53 in the preceding example in that in its upward extension it inclines forwardly so that it has a downwardly rearwardly inclined surface 78 immediately behind and under the rear and lower end of the inclined lock 71. The rear end 79 of the lock-bolt 72 which shoots down from the rear of the lock 71 is beveled to cooperate with this inclined surface 78 so that, when the lock-bolt 72 is shot downward, it pulls the upper lever-arm 53' of the setting-lever 48' forward, and with it the slidable shaft 46, disengaging its clutch-teeth 47 from the clutch-teeth 44 of the pump-operating crank shaft 25, as in the preceding example. When the bolt 72 is shot upward, it releases the arm 53' to move forward; which the arm does under the action of the spring 52, allowing the clutch-teeth 47 and 48 to mesh,

and connecting the pump for operation by the differential ring-gear 3 through the gear 23. It will therefore be seen that setting the alarm device for operation also locks the entire casing part 68 against removal from the vehicle; yet this casing part 68 is as readily removed as any other when the device is not set for alarm operation, because the unsetting simultaneously unlocks the part 68 from the other part of the casing, so that it may be readily removed by merely taking out the bolts by which it is connected to said other part.

It will be noted that the long bore, through which the lock cylinder 76 extends, 80 and the upper end of the setting-lever arm 53' are so relatively positioned that it is practically impossible to manipulate the lever by any instrument inserted through the bore in case the lock and its cylinder 85 should be knocked out of position. Such a relation of the lock to the setting-lever is therefore of value in connection with any type of casing, whether it be necessary to lock one section thereof to the other or not. 90

Having fully described our invention, what we claim as new and desire to secure by Letters Patent is:

1. In a detection signal, in combination with a structure and an element movably supporting said structure whereby said element moves when the structure is moved, a sound-producing device, mechanism to mechanically operate said device, and an exclusively lock-controlled driving connection 100 between said mechanism and said element.

2. In a detection signal, in combination with a structure and an element movably supporting said structure whereby said element moves when the structure is moved, a sound-producing device, mechanism to mechanically operate said device, an exclusively lock-controlled driving connection between said mechanism and said element, a single casing inclosing said device, said mechanism and said driving connection, and controlling means accessible from outside said casing for effecting the lock-controlling operation.

3. In a detection signal, in combination with a structure and an element movably supporting said structure whereby said element moves when the structure is moved, a sound-producing device, and exclusively lock-controlled mechanism operatively connecting said element and said device for operation of said device by said element when said element moves under one condition permitted by the lock-control, or inoperatively disconnected whereby said device is left inoperative upon movement of said element under another condition permitted by said lock-control.

4. In a detection signal, in combination with a structure and an element movably

- supporting said structure whereby said element moves when the structure is moved, a bearing for said element, a sound-producing device, exclusively lock-controlled mechanism operatively connecting said element and said device for operation of said device by said element when said element moves under one condition permitted by the lock-control, or inoperatively disconnected whereby said device is left inoperative upon movement of said element under another condition permitted by said lock-control, and supporting means for said mechanism in fixed relation to said bearing.
- 5 15 20 25 30 35 40 45 50 55 60 65 70 75 80 85 90 95 100 105 110 115 120 125 130
5. In a detection signal, in combination with a structure and an element movably supporting said structure whereby said element moves when the structure is moved, a bearing for said element, a sound-producing device, mechanism to mechanically operate said device, an exclusively lock-controlled driving connection between said mechanism and said element, and supporting means for said driving connection in fixed relation to said bearing.
6. In a detection signal, a combination with a structure and an element movably supporting said structure whereby said element moves when the structure is moved, a bearing for said element, a sound-producing device, mechanism to mechanically operate said device, an exclusively lock-controlled driving connection between said mechanism and said element, a single casing inclosing said device, said mechanism and said driving connection and in fixed relation to said bearing, and controlling means accessible from outside said casing for effecting the lock-controlling operation.
7. In a detection signal, in combination with a structure and an element movably supporting said structure whereby said element moves when the structure is moved, a sound-producing device, mechanism in permanent operative connection with said device to mechanically operate said device, and an exclusively lock-controlled driving connection between said mechanism and said element.
8. In a detection signal, in combination with a structure and an element movably supporting said structure whereby said element moves when the structure is moved, a bearing for said element, a sound-producing device, mechanism in permanent operative connection with said device to mechanically operate said device, an exclusively lock-controlled driving connection between said mechanism and said element, and supporting means for said driving connection in fixed relation to said bearing.
9. In a detection signal, in combination with a structure and an element movably supporting said structure whereby said element moves when the structure is moved, a

sound-producing device, mechanism in permanent operative connection with said device to mechanically operate said device, an exclusively lock-controlled driving connection between said mechanism and said element, a single casing inclosing said device, said mechanism and said driving connection, and controlling means accessible from outside said casing for effecting the lock-controlling operation.

10. In a detection signal, in combination with a structure and an element movably supporting said structure whereby said element moves when the structure is moved, a bearing for said element, a sound-producing device, mechanism in permanent operative connection with said device to mechanically operate said device, and exclusively lock-controlled driving connection between said mechanism and said element, a single casing inclosing said device, said mechanism and said driving connection and in fixed relation to said bearing, and controlling means accessible from outside said casing for effecting the lock-controlling operation.

11. In a detection signal, in combination with a movable means, a sound-producing device, operating means to operate said device, a lock-controlled actuating connection between said operating means and said movable means, a single casing inclosing said device, said operating means and said actuating connection, and controlling means accessible from outside said casing for effecting the lock-controlling operation, said casing comprising separable sections, and said device, actuating connection and controlling means all being mounted entirely on one of said sections.

12. In a detection signal, in combination with a movable means, a sound-producing device, operating means to operate said device, a lock-controlled actuating connection between said operating means and said movable means, a single casing inclosing said device, said operating means and said actuating connection, and controlling means accessible from outside said casing for effecting the lock-controlling operation, said casing comprising separable sections, and locking means to lock said sections together, under the control of said controlling means.

13. In a detection signal, in combination with a movable means, a sound-producing device, operating means to operate said device, a lock-controlled actuating connection between said operating means and said movable means, a single casing inclosing said device, said operating means and said actuating connection, and controlling means accessible from outside said casing for effecting the lock-controlling operation, said casing comprising separable sections, and said device, actuating connection and con-

- trolling means all being mounted entirely on one of said sections, and locking means on said one of said sections to lock said sections together, under the control of said controlling means.
14. In a detection signal, in combination with a movable means, a sound-producing device, operating means to operate said device, a lock-controlled actuating connection between said operating means and said movable means, a single casing inclosing said device, said operating means and said actuating connection, and controlling means accessible from outside said casing for effecting the lock-controlling operation, said casing comprising separable sections, and said device, actuating connection and controlling means all being mounted entirely on one of said sections, engaging means near one side of one of said sections, engaging with the other section, and locking means near an opposite side of said one of said sections to lock said sections together in conjunction with said engaging means, said locking means being under the control of said controlling means, and said opening interiorly of said casing being directed away from said actuating connection.
15. In a detection signal, in combination with a movable means, a pneumatically-operating sound-producing device, and lock-controlled pneumatic-pressure-raising mechanism operatively connected to operate said device by movement of said movable means under one condition permitted by the lock-control and inoperatively disconnected under another condition permitted by said lock-control whereby said device is left inoperative upon movement of said movable means.
16. In a detection signal, in combination with a movable means, a sound-producing device, operating means to operate said device, a lock-controlled actuating connection between said operating means and said movable means, a single casing inclosing said device, said operating means and said actuating connection, and having an access opening, and controlling means accessible through said access opening for effecting the lock-controlling operation, said opening interiorly of said casing being directed away from said actuating connection.
17. In a detection signal, in combination with a movable means, a sound-producing device, operating means to operate said device, a lock-controlled actuating connection between said operating means and said movable means, a single casing inclosing said device, said operating means and said actuating connection, and having an access opening, and controlling means accessible through said access opening for effecting the lock-controlling operation, engaging means near one side of said one of said sections, engaging with the other section, and locking means near an opposite side of said one of said sections to lock said sections together in conjunction with said engaging means, said locking means being under the control of said controlling means, and said opening interiorly of said casing being directed away from said actuating connection.
18. In a detection signal, in combination with movable means, a pneumatically-operating sound-producing device, and lock-controlled pneumatic-pressure-raising mechanism operatively connected to operate said device by movement of said movable means under one condition permitted by the lock-control and inoperatively disconnected under another condition permitted by said lock-control whereby said device is left inoperative upon movement of said movable means.
19. In a detection signal, in combination with a structure and an element movably supporting said structure whereby said element moves when the structure is moved, a pneumatically-operating sound-producing device, and lock-controlled pneumatic-pressure-raising mechanism operatively connected to operate said device by movement of said element under one condition permitted by the lock-control, and inoperatively disconnected under another condition permitted by said lock-control whereby said device is left inoperative upon movement of said element.
20. In a detection signal, in combination with movable means, a pneumatically-operating sound-producing device, and an exclusively lock-controlled pneumatic-pressure-raising mechanism operatively connected to operate said device by movement of said movable means under one condition permitted by the lock-control and inoperatively disconnected under another condition permitted by said lock-control whereby said device is left inoperative upon movement of said movable means.
21. In a detection signal, in combination with a structure and an element movably supporting said structure whereby said element moves when the structure is moved, a pneumatically-operating sound-producing device, and an exclusively lock-controlled pneumatic-pressure-raising mechanism operatively connected to operate said device by movement of said element under one condition permitted by the lock-control, and inoperatively disconnected under another condition permitted by said lock-control whereby said device is left inoperative upon movement of said element.
22. In a detection signal, in combination with movable means, a pneumatically-operating sound-producing device, and lock-controlled pneumatic-pressure-raising mechanism in permanent operative connection

with said device to operate said device by movement of said movable means under one condition permitted by the lock-control and inoperatively disconnected under another 5 condition permitted by said lock-control whereby said device is left inoperative upon movement of said movable means.

23. In a detection signal, in combination with movable means, a pneumatically-operating sound-producing device, pneumatic-pressure-raising mechanism to operate said device, a lock-controlled driving connection between said mechanism and said movable means, a single casing inclosing said device, 10 said mechanism and said driving connection, and controlling means accessible from outside said casing for effecting the lock-controlling operation.

24. In a detection signal, in combination with a structure and an element movably supporting said structure, whereby said element moves when the structure is moved, a pneumatically-operating sound producing device, pneumatic-pressure-raising mechanism to operate said device, and a lock-controlled driving connection between said mechanism and said element, a single casing inclosing said device, said mechanism and said driving connection, and controlling 25 means accessible from outside said casing for effecting the lock-controlling operation.

25. In a detection signal, in combination with a differential mechanism, its casing and a movable element thereof in said casing, 30 a sound-producing device, operating means to operate said device, a lock-controlled actuating connection between said operating means and said movable element, said device, operating means and connection all being 35 inclosed in said casing, and controlling means accessible from outside said casing for effecting the lock-controlling operation, said casing comprising separable sections, and said device, actuating connections and controlling means all being contained entirely 40 in one of said sections.

26. In a detection signal, in combination with a differential mechanism, its casing and a movable element thereof in said casing, 45 a sound-producing device, operating means to operate said device, a lock-controlled actuating connection between said operating means and said movable element, said device, operating means and connection all being 50 inclosed in said casing, and controlling means accessible from outside said casing for effecting the lock-controlling operation by projecting to disconnect said actuating connection, whereby bodily removal 55 of said controlling means permits said connection to be connected.

27. In a detection signal, in combination with a differential mechanism, its casing and a gear thereof in said casing, a sound-producing device, operating means to oper-

ate said device, a gear meshing with said gear of the differential mechanism, and a releasable driving connection between this gear and said operating means, said device, operating means, gear and driving connection all being inclosed in said casing. 70

28. In a detection signal, in combination with a differential mechanism, its casing and a movable element thereof in said casing, a pneumatically operating sound-producing device, pneumatic-pressure-raising mechanism to operate said device, and a releasable driving connection between said mechanism and said element, said device, mechanism and connection all being inclosed in said 75 casing. 80

29. In a detection signal, in combination with a differential mechanism, its casing and a gear thereof in said casing, a pneumatically-operating sound-producing device 85 in said casing, an operating mechanism for said sound-producing device, in said casing, comprising a cylinder with an inlet, a valved pneumatic connection from said cylinder to said device, a plunger in said cylinder, a crank, operative connection between said crank and said plunger, a gear in said casing in mesh with said gear of said differential mechanism, and releasable operative connection between said gear and said 90 crank. 95

30. In a detection signal, in combination with a differential mechanism, its casing and a gear thereof in said casing, a pneumatically-operating sound-producing device in 100 said casing, an operating mechanism for said sound-producing device in said casing, comprising a cylinder with an inlet, a valved pneumatic connection from said cylinder to said device, a plunger in said cylinder, a crank, operative connection between said crank and said plunger, a gear in said casing in mesh with said gear of said differential mechanism, a slidable shaft turning with this gear, slidable toward and away 105 from said crank, clutch connections on said crank and said slidable shaft, respectively, a setting lever engaging said slidable shaft, a spring engaging said lever to slide said shaft into clutching connection with said 110 crank, and a lock in said casing comprising a bolt normally bearing on said lever and holding said shaft out of said connection, and means accessible from the outside of 115 said casing for operating said lock to move said bolt out of said normal position and permit said connection of said shaft and said crank. 120

31. In a detection signal, in combination with a differential mechanism, its casing 125 and a gear thereof in said casing, a pneumatically-operating sound-producing device in said casing, an operating mechanism for said sound-producing device, in said casing, comprising aligned cylinders with inlets, 130

valved pneumatic connections from said cylinders to said device, plungers in said cylinders, a yoke connecting said plungers and having a transverse slot, a crank having a 5 wrist in said slot, a gear in said casing in mesh with said gear of said differential mechanism, and releasable operative connection between said gear and said crank.

32. In a detection signal, in combination 10 with a differential mechanism, its casing and a gear thereof in said casing, a pneumatically-operating sound-producing device in said casing, an operating mechanism for said sound-producing device, in said casing, 15 comprising aligned cylinders with inlets, valved pneumatic connections from said cylinders to said device, plungers in said cylinders, a yoke connecting said plungers and having a transverse slot, a crank having a 20 wrist in said slot, a gear in said casing in mesh with said gear of said differential mechanism, a slidable shaft turning with this gear, toward and away from said crank, clutch connections on said crank and said 25 25 slidable shaft, respectively, a setting lever engaging said slidable shaft, a spring engaging said lever to slide said shaft into clutching connection with said crank, and a

lock in said casing comprising a bolt normally bearing on said lever and holding said 30 shaft out of said connection and means accessible from the outside of said casing for operating said lock to move said bolt out of said normal position and permit said connection of said shaft and said crank. 35

33. In a detection signal, in combination with a movable means, a sound-producing device, operating means to operate said device, a lock-controlled actuating connection between said operating means and said movable means, a single casing inclosing said device, said operating means and said actuating connection, and controlling means accessible from outside said casing for effecting the lock-controlling operation, said casing comprising separable sections fastened together, means inside said sections whereby they are prevented from sliding relatively to each other when unfastened, and locking means to lock said sections together, under 40 45 50 the control of said controlling means.
